(Cl. D33—11)

FIG. 1

FIG. 2

FIG. 3

FIG 4

FIG 5

FIG 6

FIGURE 1 is a perspective view of a tablet arm chair embodying my new design;

FIGURE 2 is a front elevational view thereof;

FIGURE 3 is a side elevational view thereof;

FIGURE 4 is a rear elevational view thereof;

FIGURE 5 is a top plan view thereof; and

FIGURE 6 is a bottom plan view thereof, a book rack indicated in dotted lines in FIGURES 1, 2, 3 and 4 being omitted from FIGURE 6 for purposes of better illustration.

The dominant features of my design reside in those portions shown in full lines on the drawing.

I claim:

The ornamental design for a tablet arm chair, substantially as shown and described.
